The ornamental design for display panel with a computer icon for use with a valve controller, as shown and described.

DESCRIPTION

FIG. 1 is a front view of a display panel for use with a valve controller, showing our new design; and,

FIG. 2 a front view of a second embodiment thereof. The three outermost oval broken lines represent outer boundary features that extend around the perimeter of the display panel while the inner oval broken line represents a visual cue that delineates a central region of the display panel; the broken lines form no part of the claimed design.
